SAFETY PILOT FOR GAS HEATERS

Ernst R. Koppel, Wauwatosa, Wis., assignor to
 A. O. Smith Corporation, Milwaukee, Wis., a
 corporation of New York

Application August 14, 1941, Serial No. 406,786

6 Claims. (Cl. 158—117.1)

This invention relates to a safety pilot for gas heaters, and has been applied to the control of pilots for thermostatically operated heaters in heating water for domestic use.

The principal object of the invention is to provide a safety control for the pilot flame so that should the pilot become extinguished, both the main gas supply to the burner and that to the pilot would be shut off and there would be no leakage of gas through the pilot burner.

Another object is to provide such a control with an alternative passage with manual control for supplying gas to the pilot burner for starting.

Another object is to provide that the manual control referred to is required to be in a position closing the alternative passage when the pilot is heated and the main safety valve is open.

Other objects and advantages of the invention will be explained in connection with the description of a number of embodiments illustrated in the accompanying drawing.

In the drawing:

Figure 1 is a front elevation of the control unit of one embodiment, showing the pilot valve handle in starting position;

Fig. 2 is a side elevation of the unit taken from the right of Fig. 1 showing the manual shut off valve closed;

Fig. 3 is a view similar to Fig. 1, partly in section, showing the pilot valve in normal heater operating position and showing the main gas valve open;

Fig. 4 is a side elevation of Fig. 3, viewed from the right;

Fig. 5 is a vertical section taken on line 5—5 of Fig. 3 showing the main thermostat safety control valve;

Fig. 6 is a front elevation showing a unit, similar to that in Fig. 1, in which the lugs on the shut off valve are eliminated;

Fig. 7 is a front elevation partly in section of a modified form of unit in which the manual shut off valve and auxiliary pilot starting valve are disposed to operate together, the valve being shown in pilot lighting position;

Fig. 8 is a view similar to Fig. 7 of another form in which a sliding pilot valve is employed, showing the valves in pilot lighting position;

Fig. 9 is a section on line 9—9 of Fig. 8; and

Fig. 10 is a section on line 10—10 of Fig. 8, showing the pilot valve in normal heater operating position.

In accordance with the invention, a thermostatically controlled valve provides gas from the

low pressure side of the main shut off valve to the pilot, and a manually set valve is provided to supply gas for starting the pilot from the high pressure side of the main shut off valve.

By low and high pressure sides it is not intended to indicate that the gas is at any different pressure on the two sides when the valve is open, but that there is a difference when the valve is closed, and the high pressure side is that of the inlet to the valve while the low pressure side is that of the outlet from the valve.

Referring to the drawing, the unit comprises a cast metal body 1 providing two main valve chambers, one for the manual shut off valve 2 and the other for the thermostatically controlled snap shut off valve 3.

A pilot burner 4 is threaded at its inner end into the casing 1 and a thermostat 5 extending parallel to the burner tube and above it is also threaded into the casing. The central rod 6 of the thermostat is connected to and operates valve 3. The construction of valve 3 and thermostat 5 may be similar to present day standard thermostat valves used on the main burner for water heaters.

The hand shut off valve 2 may also be of standard construction usually comprising a conical body 7, having a passage 8 therethrough disposed to register with an inlet passage 9 and outlet passage 10 in the body 1, when in open position, and to be turned so as to fall to register with the passage 9 when in the closed position. The valve 2 has a handle 11 for turning it.

The gas for the main burner passes through inlet 9, passage 8, outlet 10, and through valve 3 to pipe 12 leading to the burner control valve. Thus, in order to supply gas to the main burner, both the manual shut off valve 2 and thermostatically controlled shut off valve 3 must be open. Since the valve 3 is controlled by heat from the pilot flame, it shuts off the entire gas supply in case the pilot flame goes out.

The pilot burner 4 is supplied with gas through passage 13, and a two-way valve 14 is disposed for connecting passage 13 either to passage 15 leading from the low pressure side of valve 3, or to passage 16 leading from the gas supply duct 9.

The valve 14 comprises a conical member 17 secured for turning in a complementary opening in body 1. The passage 13 connects with the inner end of member 17, the latter having an axial hole therethrough. A radial hole 18 through one side of member 17 connects the passage 13 to either the passage 15 or 16. A center

plug 18 screws into the axial opening in member 17 and serves to adjust the opening of hole 18 to adjust the supply of gas to the pilot flame. A cap 20 covers the outer end of member 17 to protect against leakage of gas past the plug 18 and has secured thereto the manual operating lever 21 for rotating the member 17.

The operating lever 21 is pressed to normal position by spring 22 so that during normal operation of the heater gas is supplied to the pilot through passage 15, hole 18, member 17 and passage 13.

Should the pilot flame become extinguished, thermostat 5 cools off and valve 3 closes, thereby shutting off the supply of gas to both the pilot burner and the main heating burner. Gas will not escape through either burner while valve 3 is closed.

To light the burner the operator turns the manual shut off valve 2 to "off" position and turns the pilot valve 14 to the right by means of lever 21 until hole 18 registers with passage 16 so as to supply gas from inlet 8 through passage 16, hole 18, member 17 and passage 13 to the pilot burner. He then lights the pilot.

After the pilot flame becomes hot, thermostat 5 operates to open valve 3 and the operator turns valve 2 to "on" position, and releases lever 21, which returns to normal position by reason of spring 22 and supplies gas to the pilot burner from the low pressure side of valve 3 through passage 15.

Several different constructions may be employed for holding the lever 21 to the right against the spring 22 while the pilot is lighted and heats thermostat 5.

In the construction of Figures 1 to 5, inclusive, a lug 23 is disposed on the body 1 to hold lever 21 down while the pilot is being lighted. The lever 21 is released from lug 23 either manually or by a cam 24 on handle 11 when valve 2 is turned to open position.

In Fig. 6 the lugs 23 and 24 are eliminated and lever 21 is held in starting position solely by the operator. Upon operation of thermostat 5 the operator releases lever 21 and it returns to normal operating position.

In Fig. 7 a modified form is shown. In this embodiment the valve 2' in addition to supplying the burner through port 8' serves also as the pilot valve by providing an auxiliary passage 25 in conical body 7' positioned to connect passage 16' to the inlet 8'. The radial location of passage 25 relative to port 8' is such that it connects the passages 8' and 16' when the valve handle 11' is turned about 90° from either "on" or "off" position. Thus, the port 8' is shut off when passage 25 registers with inlet 8' and the latter is opened through port 8', valve 3' and passage 15' leading from the low pressure side of valve 3' when valve 2' is open. Port 8' is closed to both ports 8' and 16' when handle 11' is turned to off position.

In Figures 8, 9 and 10 the pilot valve is a slide valve operated manually by a push button 26. The cylindrical valve body 27 is normally biased outwardly by a spring 28 at its rear end. The body 27 has a longitudinal passage 29 extending from its rear end to a point near its forward end where the passage connects with a transverse passage 30 extending diametrically through the body. Two radial passages 31 and 32 connect with passage 29 intermediate the rear end of body 27 and the passage 30. The button 26 is preferably non-circular in cross section and

passes through a complementary opening in the casing to prevent turning of the body.

When starting the burner, the push button 26 is pressed inwardly moving valve body 27 against spring 28. This effects the registry of passage 30 with a passage 33 leading from the gas supply passage 8' and with a passage 34 leading to the pilot burner 4'. Both radial passages 31 and 32 are closed at this time. When the pilot thermostat 5' becomes heated valve 3' is opened and the operator can then release button 26. A needle valve 35 controls the gas supply to the pilot burner 4'.

When the burner is on, as shown in Fig. 10, the radial passage 31 registers with passage 36 leading from the low pressure side of the main thermostat valve 3', and radial passage 32 registers with passage 34 leading therefrom to the pilot burner 4'. The ends of passage 36 are closed by the housing surrounding the valve.

The invention is a substantial improvement over previous constructions since it provides absolute safety in case the pilot becomes extinguished. At the same time, it allows for safe and easy starting of the burner.

Various embodiments of the invention may be employed within the scope and spirit thereof as set forth in the accompanying claims.

The invention is hereby claimed as follows:

1. In a safety control for gas heaters employing a pilot burner and a safety shut off valve operated thermostatically in response to heat therefrom, a manual shut off valve on the high pressure side of said safety shut off valve for supplying gas thereto, means manually operable to supply gas to the pilot for starting the pilot burner when said manual shut off valve is closed, and means operable in response to the opening of said manual shut off valve after the safety valve opens in response to heat from the pilot burner for supplying gas to the pilot from the low pressure side of said safety valve.

2. In a safety control for gas heaters employing a pilot burner and a safety shut off valve operated thermostatically in response to heat therefrom, a manual shut off valve on the high pressure side of said safety shut off valve for supplying gas thereto, means manually operable to supply gas to the pilot from the high pressure side of said shut off valves for starting the pilot burner when said manual shut off valve is closed, and means operable in response to the opening of said manual shut off valve to supply gas to the pilot from the low pressure side of said safety valve after the safety valve opens in response to heat from the pilot burner.

3. A safety control for gas heaters employing a pilot burner for lighting the heater, comprising a main shut-off valve having a valve body containing passages supplying gas to the heater, a thermostat responsive to heat from the flame of the pilot burner for operating said shut-off valve, said valve body containing passages for supplying gas to the pilot burner from opposite sides of the main shut-off valve, a two-way valve controlling said last-named passages and alternatively supplying gas to the pilot burner from either side of the main shut-off valve, means normally biasing said two-way valve to supply gas to the pilot burner from the low pressure side of the main shut-off valve, and means for manually operating said two-way valve to supply gas to the pilot burner from the high pressure side of the main shut-off valve for starting the burner.

4. A safety control for gas heaters employing a

pilot burner for lighting the heater, comprising a main shut-off valve having a valve body containing passages supplying gas to the heater, a thermostat responsive to heat from the flame of the pilot burner for operating said shut-off valve, said valve body containing passages for supplying gas to the pilot burner from opposite sides of the main shut-off valve, a two-way valve controlling said last-named passages and alternatively supplying gas to the pilot burner from either side of the main shut-off valve, means normally biasing said two-way valve to supply gas to the pilot burner from the low pressure side of the main shut-off valve, means for manually operating said two-way valve to supply gas to the pilot burner from the high pressure side of the main shut-off valve for starting the burner, and means for retaining said two-way valve in starting position against the action of said biasing means.

5. A safety control for gas heaters employing a pilot burner for lighting the heater, comprising a valve body having passages for supplying gas to the heater, a manual shut-off valve controlling said passages, a thermostatically operated shut-off valve in series with said manual shut-off valve and operable in response to heat from the flame of the pilot burner, said valve body containing passages for supplying gas to the pilot burner from either the low pressure side of the shut-off valve nearest the heater or the high pressure side of the shut-off valve farthest from the heater, a two-way valve controlling said last-named passages and alternatively supplying gas to the pilot burner from either side of the main

shut-off valves, means normally biasing said two-way valve to supply gas to the pilot burner from the low pressure side of the shut-off valves, means for manually operating said two-way valve to supply gas to the pilot burner from the high pressure side of the shut-off valves for starting the burner, means for retaining said two-way valve in starting position against the action of said biasing means, and means on said manual shut-off valve for releasing said retaining means and preventing its operation when said manual shut-off valve is moved to open position.

10 6. A safety control for gas heaters employing a pilot burner for lighting the heater, comprising a manual shut-off valve having a valve body containing passages for supplying gas to the heater and passages for supplying gas to the pilot burner from opposite sides of the shut-off valve, a two-way valve controlling said last-named passages and alternatively supplying gas to the pilot burner from either side of said shut-off valve, means normally biasing said two-way valve to supply gas to the pilot burner from the low pressure side of the shut-off valve, means for manually operating said two-way valve to supply gas to the pilot burner from the high pressure side of the shut-off valve for starting the burner, means for retaining said two-way valve in starting position against the action of said biasing means, and means on said manual shut-off valve for releasing said retaining means and preventing its operation when said manual shut-off valve is moved to open position.
